UNITED STATES PATENT OFFICE.

FRANK LA BARE, OF OWATONNA, MINNESOTA, ASSIGNOR TO OWATONNA MANUFACTURING COMPANY, OF OWATONNA, MINNESOTA, A CORPORATION.

COMBINED CHURN AND BUTTER-WORKER.

No. 866,038.

Specification of Letters Patent.

Patented Sept. 17, 1907.

Application filed May 12, 1906. Serial No. 316,443.

To all whom it may concern:

Be it known that I, FRANK LA BARE, of Owatonna, Steele county, Minnesota, have invented certain new and useful Improvements in Combined Churns and 5 Butter-Workers, of which the following is a specification.

This invention relates to improvements in combined churning and butter-workers and particularly in that type of machines in which a pair of butter-working rolls is 10 arranged within a revoluble drum and are held, during the butter-working operation, in a stationary position while each of said rolls is rotated inwardly towards the other upon its own axis and the butter which is carried up by the wall of the drum and flights thereon is 15 dropped onto the rolls and is passed between them, this operation being repeated as often as necessary until the butter is completely worked.

The object of my present invention is to obviate the necessity of using a loose or independent head at one 20 end of the churn that is clamped to the head of the drum during the churning operation and is released therefrom and held in a stationary position during the butter-working operation.

Another object of the invention is to arrange the butter-working rolls within the drum in position to more 25 certainly receive the butter that is carried up by the flights so as to insure a more uniform working thereof.

Other objects of the invention will appear from the following detailed description, taken in connection 30 with the accompanying drawings, in which

Figure 1 is a longitudinal, vertical section of a combined churn and butter-worker embodying my invention. Fig. 2 is a horizontal section of the same. Fig. 3 is a plan view and partial section showing the driving 35 mechanism. Fig. 4 is a vertical section of the machine on line 4—4 of Fig. 1. Fig. 5 is a vertical section on line 5—5 of Fig. 1. Fig. 6 is a vertical section on line 6—6 of Fig. 1. Figs. 7 and 8 are details of the cross-head lock. Fig. 9 is a longitudinal, vertical section 40 showing a slightly modified construction.

In all of the drawings, 2—2 and 2' represent the legs or standards of the machine and 3—3 represent horizontal bars or girders connected to the standards 2—2 and having preferably the standard 2' supported thereon. 45 These standards and the girders constitute the frame of the machine.

4 represents the drum of the machine, which may be 50 of any suitable length and diameter and which is provided, upon its interior near the circumferential wall thereof, with the flights or shelves 5. This drum is provided at its opposite ends with the hollow gudgeons 6 and 7, mounted in bearings on the standards 2 and forming a revoluble support for said drum. Said gudgeons are preferably formed integrally with the spiders

8 and 9 which are bolted or otherwise suitably secured 55 to the heads of the drum.

Arranged in the drum are the butter-working rolls 10, which are located parallel to each other and supported at their rear ends by suitable gudgeons mounted in bearings in a cross-head 11. This cross-head is provided with a shaft 12 that extends through a stuffing box 13 in the head of the drum and through the hollow gudgeon 6 and has mounted, upon its outer end, the beveled gear 13'.

The front or gear end of the churn drum is provided 65 with a central opening in which is fitted a sectional friction head 14. This sectional head fits within the opening in the drum head and a cream and water tight joint is formed between the circumference of said sectional head and the wall of the opening in the drum 70 head. This joint may be formed in any suitable manner. I prefer to provide the wall of the opening with a flanged ring 15 fitting therein and bolted to said drum head and to provide a suitable packing between said ring and the circumferential wall of the sectional 75 head 14.

A ring 16 is arranged to project into the space between the ring 15 and the circumferential wall of the sectional head and suitable bolts 17 are provided, by means of which said ring 16 may be forced into the 80 space between the ring 15 and the circumferential wall of the sectional head for the purpose of extending the packing and tightening the joint. At this end of the machine the rolls are provided with the gudgeons 19, which extend through suitable stuffing boxes in 85 the sectional head 14 and are mounted in bearings in the depending cross-head 20, said cross-head being formed integrally with, or secured to, a tubular shaft 21 that is mounted in the drum gudgeon 7. Each of the gudgeons 19 has secured to it a gear 22 and these 90 gears mesh with each other, and formed integrally with one of said gears is a pinion or smaller gear 23 (see Fig. 2). A shaft 24 extends through the tubular shaft 21 and has its inner end projecting into a socket 25 formed in a boss on the outer surface of the sectional head 14. The shaft 24 has secured to it the pinion 26 which meshes with the pinion 23 on the gudgeon of one of the rolls and at its outer end it has secured to it the pinion 27, which is engaged by a gear 28 mounted on a stud or short shaft that is supported on the stand- 100 ard 2.

I prefer to form the sectional head 14 of metal and to secure a wooden plate 29 to its inner surface. This plate prevents the cream and butter from coming in contact with the metal head 14. I also prefer to provide a cross-head 30 that is secured to the inner side of the sectional head and supports one end of each of the roller shelves 31—31, the opposite ends of said shelves 105

being supported in the cross-head 11 (see Fig. 5). These roller shelves are arranged at each side of, and a little above, the butter-working rolls and form a sort of hopper and assist in guiding the butter dropped 5 from the flights or shelves to the rolls.

I provide means for rotating the drum at a high speed for churning and at a low speed for working the butter and I also provide means for rotating the rolls upon their axes during the butter-working operation 10 and, if preferred, the rolls may be rotated upon their axes while the drum is stationary. I also provide means for locking the cross-head in a stationary position so as to hold the rolls from whirling with the drum during the butter-working operation.

15 For the purpose of revolving the drum, I provide a horizontal frame or bridge-tree 32 secured upon the standard 2 at the gear end of the machine and in suitable boxes upon this bridge-tree and in the standard 2', I mount the driving-shaft 33 carrying, at its inner 20 end, a pinion 34 that engages with a ring gear 35 on the head of the drum. Mounted so as to rotate freely upon this shaft is the driving pulley 36 and a clutch member 37 is provided upon a sleeve 38 that is also loosely mounted upon the shaft 33. This sleeve is preferably 25 arranged within one of the shaft supporting boxes. The driving pulley can be moved longitudinally upon the shaft 33 so as to have its rim engage or disengage the clutch member 37. The sleeve 38 is also provided with a pinion 39 and the inner end of the sleeve is provided with the projections 42 forming one member of a clutch.

30 Mounted in bearings in the bridge-tree, parallel with the shaft 33, is a short shaft 43 having arranged thereon the sleeve 44 carrying, at one end, a pinion 45 and at 35 the other end a gear 46 that meshes with the pinion 39 on the sleeve 38. Secured on the shaft 43, so as to rotate therewith, is a pinion 47 and a clutch member 48 is arranged upon the hub of this pinion and a corresponding clutch member 49 is arranged upon the end 40 of the sleeve 44. The sleeve 44 is capable of being shifted slightly longitudinally on the shaft 43 so as to engage or disengage the clutch members 48 and 49. Splined upon the shaft 33 is a gear 50 having its hub provided with a clutch member 51 adapted to be engaged 45 with the clutch member 42 on the sleeve 38. The gear 50 is adapted to slide lengthwise on the shaft 33 and may be brought into mesh with the pinion 45 on the sleeve 44 or it may be moved out of mesh with said pinion and may stand in an intermediate position, 50 as indicated in dotted lines in Fig. 3, or this gear may be shifted on the shaft 33 so as to bring the clutch member 51 into engagement with the clutch member 42.

55 When it is desired to rotate the drum at a high speed for the churning operation, the gear 50 is shifted so as to bring the clutch member 51 into engagement with the clutch member 42 and the driving pulley 36 being thrown into engagement with the clutch 37, the drum will be revolved at the desired speed for the churning operation.

60 For the butter-working operation the gear 50 is moved into mesh with the pinion 45 and then the drum is revolved at a slow speed through the pinion 39, the gear 46, the pinion 45, the gear 50 and pinion 34. At the same time in order to drive the butter-working rolls, 65 the sleeve 44 is shifted so as to engage the clutch mem-

bers 48 and 49 and thereby the pinion 47 is driven and this, in turn, drives the gear 28, with which it is in mesh. This drives the pinion 27, the shaft 24, the pinion 26, the pinion 23 and the roll gears 22, rotating the rolls on their axes for the operation of working the 70 butter.

If it is desired to rotate the rolls while the drum remains stationary, the gear 50 is shifted far enough to disengage it from the pinion 45 without engaging the clutch members 42 and 51. The drum will then remain stationary while the rolls will be rotated on their axes, turning inwards toward each other. Suitable levers 52 and 53 are provided for shifting the gear 50 and the sleeve 44.

80 Mounted on and secured to the tubular cross-head shaft 21 at the front or gear end of the machine is a beveled gear 21' corresponding to the gear 13' on the cross-head shaft 12 at the opposite end of the machine. These gears are connected by means of the beveled pinion 54, shaft 55, pinions 56 and 57, horizontal shaft 85 58, pinions 59 and 60, shaft 61 and pinion 62. By this means said cross-heads are always held parallel to each other, and the butter-working rolls are also held parallel to each other, and when one of said cross-heads whirls with the drum, the other must have a similar 90 movement.

I provide means for locking one of the cross-head shafts to the drum gudgeon at one end of the machine so as to cause the cross-heads and the rolls to whirl with the drum during the churning operation, or for locking 95 said cross-head shaft to the frame of the machine, whereby said cross-heads and rolls will be held in a stationary position during the butter-working operation. For this purpose, I provide, in the outer end of the hollow gudgeon 7, a series of recesses or slots and I 100 provide a clutch sleeve 63 having corresponding fingers adapted to engage said recesses and thereby to lock said cross-head shaft to the drum gudgeon. These fingers pass through slots 64 in the gear 21' (see Fig. 7) and for the purpose of moving said clutch sleeve, I provide 105 a yoke 65 pivoted on the frame of the machine and provided with arms 66 engaging said clutch sleeve and with an operating handle 67 provided with a latch 68 adapted to engage recesses in a stationary rack 69 (see Fig. 8). When the yoke is thrown into the perpendicular position shown in Fig. 1, the fingers on the clutch sleeve are moved inward through the slots in the gear 21' and into engagement with the recesses in the outer end of the drum gudgeon 7. The yoke 65 is preferably provided with a lug or projection 70 adapted 115 to engage a recess 71 in the gear 21' and when the yoke is swung into the position shown in Fig. 8, the clutch sleeve is withdrawn from engagement with the drum gudgeon and the projection 70 engaging the slot 71 and the gear 21' locks both of the cross-head shafts and the 120 cross-heads and rolls supported by them in a stationary position.

For the purpose of holding these rolls in a horizontal position during the butter-working operation, the slot 71 is provided in the part of the gear 21' which is at the top when the rolls are in a horizontal 125 position.

In some instances it will be desired to hold the rolls in a stationary position during the churning operation and it will be noted that with this construction the rolls, when held in a horizontal position, are below the 130

- center of the drum. They may be dropped considerably more below the center than I have shown them in the accompanying drawings and with the rolls arranged in this manner (that is, dropped below the center of the drum or mounted in cross-heads suspended from the axis of the drum), the churning may be accomplished without causing the cross-heads and rolls to whirl with the drum, there being in this instance sufficient concussion from the dashing of the cream 5 from one side of the drum to the other and against the rolls and roller shelves to cause the proper churning of the cream into butter. I may also, if preferred, lock the cross-heads and rolls in such position that the rolls stand in a vertical plane, one over the other, or in any 10 other plane. This arrangement may be found particularly advantageous when it is desired to churn without causing the cross-heads and rolls to whirl with the drum. I lock the cross-heads and rolls in this position by providing another slot 71 in the gear 21' at a 15 point one-fourth of the circumference removed from the slot now shown in said gear. In some instances I prefer to employ, at the front or gear end of the drum, in place of the spider 9 having the hollow gudgeon 7, a 20 ring gudgeon 75 supported upon a ring bearing 76 secured to the standard 2. In this instance I prefer to arrange the locking yoke 65 and clutch sleeve 63 at the 25 opposite or rear end of the machine (see Fig. 9), the other parts of the structure remaining, however, substantially as already shown and described.
- 30 I do not limit myself to any particular construction for the sectional head arranged in the central opening in the main drum made with a tight joint between its circumferential wall and the wall of said opening as any form of sectional head fitting within the opening in 35 the main drum head and forming a tight joint therewith which, at the same time, is capable of permitting said sectional head to remain stationary while the drum rotates, may be employed, nor do I limit myself to the use of a stuffing box in the joint between the sectional head and the wall of said central opening.
- 40

I claim as my invention:

1. In a combined churn and butter-worker, the combination, with a revoluble drum provided with a head having a central opening, of a sectional head arranged within said opening with a permanently cream-tight joint between said sectional head and the wall of said opening, and a pair of butter-working rolls arranged within said drum, having their gudgeons projecting through said sectional head, substantially as described.
2. In a combined churn and butter-worker, the combination, with a revoluble drum provided, with a head having a central opening, of a sectional head arranged within said opening with a permanently cream-tight joint between said sectional head and the wall of said opening, 45 and a pair of butter-working rolls arranged in said drum and

having their gudgeons projecting through said sectional head, and means for holding said sectional head stationary while said drum revolves or permitting said sectional head to rotate with said drum, substantially as described.

3. In a combined churn and butter-worker, the combination with a revoluble drum provided with a head having a central opening, of a sectional head arranged within said opening with a permanently cream-tight joint between said sectional head and the wall of the opening, a pair of butter-working rolls arranged within said drum and having 60 their gudgeons projecting through said sectional head, and roll-driving gearing connected with said gudgeons outside of said sectional head, substantially as described.

4. In a combined churn and butter-worker, the combination, with a revoluble drum provided with a head having a central opening, of a sectional head arranged within said opening with a permanently cream-tight joint between said sectional head and the wall of said opening, and a pair of butter-working rolls arranged within said drum below the center thereof and having their gudgeons 65 projecting through said sectional head, substantially as described.

5. In a combined churn and butter-worker, the combination, with a revoluble drum, of a pair of butter-working rolls arranged in said drum, means supporting said rolls 80 below the axis of the drum and parallel to each other, means for holding the roll supports in a stationary position, and means for rotating the rolls on their axes during the butter-working operation.

6. In a combined churn and butter-worker, the combination with a revoluble drum, of a pair of butter-working rolls arranged in said drum, means supporting said rolls below the axis of the drum and parallel to each other, 85 means for locking the roll-supports to the drum, whereby said rolls whirl with the drum during the churning operation, or for holding said roll-supports in a stationary position during the butter-working operation.

7. In a combined churn and butter-worker, the combination, with a revoluble drum, of a pair of butter-working rolls arranged in said drum, means supporting said rolls 90 below the axis of the drum and parallel with each other, means for rotating the drum, and means for holding the roll-supports in a stationary position while said drum is being rotated.

8. In a combined churn and butter-worker, the combination, with a revoluble drum, of a pair of butter-working rolls arranged in said drum, means supporting said rolls 95 parallel with each other, means for rotating the drum, and means for locking the roll supports in a stationary position, while the drum is rotating, with the rolls in 100 either a horizontal or a vertical plane.

9. In a combined churn and butter-worker, the combination, a revoluble drum, of a pair of butter-working rolls arranged in said drum, means supporting said rolls parallel with each other, means for rotating the drum, and 110 means for locking the roll supports in a stationary position, while the drum is rotating, with the plane of the rolls at any desired angle.

In witness whereof, I have hereunto set my hand this 25th day of April 1906.

FRANK LA BARE.

Witnesses:
